(57) **CLAIM**

The ornamental design for a phone, as shown and described.

DESCRIPTION

FIG. 1 is a front perspective view of a phone in an open position;

FIG. 2 is a rear perspective view of the phone shown in FIG. 1;

FIG. 3 is a front elevational view of the phone shown in FIG. 1;

FIG. 4 is a side elevational view of the phone shown in FIG. 1; and,

FIG. 5 is a front perspective view of the phone shown in FIG. 1 in a closed position.

The outermost broken lines of the display and the individual keys represent the bounds of the claimed design, all the other broken lines are directed to environment and are for illustrative purposes only; the broken lines form no part of the claimed design.

1 Claim, 3 Drawing Sheets
